APPARATUS FOR TESTING MATERIALS
HAVING PLASTIC FLOW CHARACTERISTICS

Robert B. Faris, Jr., Solon, Harley F. Hardman, Wickliffe, Harrison M. Stine, East Cleveland, and Melvin M. Fink, Parma, Ohio, assignors to The Standard Oil Company, Cleveland, Ohio, a corporation of Ohio

Application May 6, 1950, Serial No. 160,546

3 Claims. (Cl. 73—88.5)

1

In testing strength of materials by force applied at an intermediate point to a test piece or bar resting on two spaced knife edge supports, the apparatus now commonly in use is of the "impact" form and the "shock-loading" form. In the "impact" type of apparatus, a high force is applied instantaneously, and the energy required to break the sample is determined; or this instantaneous force is increased and successively applied until the test piece is broken. In the "shock-loading" type, weights are applied, being added in succession until the load breaks the sample. In both of these, the characteristic is that there is not a constant rate of application of pressure, nor a constant rate test of deformability. Materials for some usages, and some kinds of materials could be more satisfactorily tested if the deformation undergone were at a constant rate. In the present invention, a constant drive rate is applied to the test sample, and it becomes possible to determine deformability under high constant rate of deformation application, as well as to determine breakage behavior of materials generally. Other objects and advantages will appear from the following description.

To the accomplishment of the foregoing and related ends, said invention then comprises the features hereinafter fully described and particularly pointed out in the claims, the following description and the annexed drawing setting forth in detail certain illustrative embodiments of the invention, these being indicative, however, of but a few of the various ways in which the principle of the invention may be employed.

In said annexed drawing, the sole figure is a side elevational, partly schematic showing of apparatus in accordance with the invention.

The sample or piece to be tested is supported on knife-edge-type spaced supports, and an opposed intermediate edge is forced against the piece at a constant high rate of speed. As illustrated in the drawing, the test piece T is supported on edges 2, 3, and an opposed edge 4 at an intermediate point is forced against the test piece by high speed constant rate means. In the illustration, this is shown as a hydraulic cylinder 5 and piston 6 supplied with a pressure fluid, for instance oil, from a reservoir 7 by a constant-drive pump 8. The supply line 9 to the cylinder proceeds through a selector valve 10, which when turned one way ports the flow of oil through the pipe 11 to the cylinder beneath the piston and at the same time ports an exhaust through pipe 12 and pipe 13 from the other end of the cylinder

5 back to the reservoir; and, vice versa, when the selector valve is turned the other way, it ports the flow of oil through pipe 12 to the cylinder above the piston and at the same time ports oil back from beneath the piston through pipe 11 and pipe 13 to the reservoir. Additionally, a relief valve 15 is provided in the pipe 9, this being of the well known type which, set to a predetermined pressure, will allow return of oil from the cylinder through pipe 17 back to the reservoir. Thus, with the selector valve 10 set to feed pressure fluid into the cylinder below the piston, the piston is raised to the top, while fluid thereabove is exhausted back to the reservoir 7, and then 15 when the piston is in its uppermost position, the mounting pressure will exceed the set-point for the relief valve 15, which then diverts the surplus fluid back to the reservoir through pipe 17, maintaining the piston in position.

20 The lower end of the piston rod 20 has secured to it, as by a nut 21, an elliptical flat band spring 22, and opposite to the end of the piston, the edge member 4 is similarly secured to the band, as by a nut 23. The nuts 21 and 23 engage the respective portions of elements 20 and 4 which pass through holes in the spring band. Interposed between the end of the piston and the edge member 4 is a coil spring or booster spring 25, which normally holds the edge member and piston end 25 and elliptical spring in predetermined relationship, but which on application of pressure to the piston allows a slight compression of the elliptical band 22. To indicate the force or stress applied, the elliptical spring 22 is provided with strain gauges 27, 28, these being of any suitable or known commercial form whose resistance varies with the surface deformation of the object to which they are attached, e. g. the Baldwin Locomotive Company strain gauge. They are in electric circuits with a dual Wheatstone bridge and voltage amplifiers which operate suitable indicating means. Conveniently this may be an oscillograph to give a permanent record of the test. Engaging a collar 30 on the piston rod 20, and 40 movable therewith is the end of a flat spring 31, whose other end is anchored at a fixed point, such as post 32 by a nut 33. This spring also carries strain gauges 34 above and below, and these are in circuit with the dual Wheatstone bridge and amplifiers and dual indicator or oscillograph. This arrangement measures the amount of motion of the movable edge member. The characteristics of the instrumentation are such as to give instantaneous and continuous 45 stress-strain relationships. Thus, the applica-

tion of dimensional data allows a calculation of moduli of elasticity and rupture as well as ultimate deformability.

The electrical circuits shown in the apparatus diagram consist of two entirely independent electrical channels, each starting with a Wheatstone bridge containing strain gauges and ending in a recording pen of an oscilloscope. In the top circuit, two 1,000 ohm resistance wire strain gauges 34 are placed in two arms of the Wheatstone bridge in such a manner that any influence which affects both gauges alike produces no unbalance of the bridge, while opposite influences, such as compression of one and tension of the other, produce twice the unbalance which would be caused if a single gauge were used. The use of these gauges as sensing elements is such that the quantity being measured always influences the two gauges oppositely while changes such as temperature affect both gauges alike and cause no output. Variable resistors 35 and 36 are coarse and fine bridge balancing controls, while the switch 37 allows the operator to choose one of the three unity-ratio arms 38 such that the bridge will have maximum sensitivity. (Maximum sensitivity occurs when all four arms of a bridge have equal resistance.) Switch 40 and resistor 39 allow the introduction of a small, reproducible unbalance into the bridge for calibrating purposes. The battery 41 supplies a direct current voltage to the bridge, and this supply voltage is regulated in steps by switch 42 and continuously over the range between steps by the variable resistor 43. Switch 44 permits the galvanometer 47 to be switched into one or the other bridge circuits to aid in balancing or to disconnect the galvanometer entirely. Switch 45 and resistor 46 provide a shunt for the galvanometer so that its sensitivity may be reduced. The output of the bridge is fed to a direct current amplifier 48, the output of which is fed to ink-pen oscilloscope channel 49 of a dual channel oscilloscope 50. The sensitivity and calibration of this entire circuit is controlled by the supply voltage and the amplifier gain. In practice, the system is calibrated statically by using a known input to the gauges and recording the deflection of the oscilloscope pen. At the same time, the deflection caused by operating switch 40 is recorded. At any subsequent time the system can be re-calibrated by adjusting the supply voltage and amplifier gain so that the previously recorded deflection of the oscilloscope pen is obtained when switch 40 is operated.

The lower circuit operates in exactly the same manner as the upper with the exception of the way in which the strain gauges are used. In this case, it was not possible to obtain two opposite forms of the quantity to be measured, so only one arm of the bridge contains an "active" gauge. However, a "dummy" gauge is used for the other arm. A "dummy" gauge is one which is subjected to as many extraneous influences affecting the active gauge as is possible (such as temperature, humidity, etc.), so that these influences will still tend to cancel in the bridge circuit.

In making a test, the pump 8 is started, this forcing a constant rate of flow of oil in the line 9. The selector valve 10 being set to divert the fluid through pipe 11, the piston is raised. Then, the test piece T is positioned on the support edges 2, 3. Such piece may be of dimensions suitable for the character of the material tested, and by adhering to dimensions standardized for each general kind of material, comparative results are

obtained. The piston 6 having reached the top of the cylinder, the building pressure opens the relief valve 15 and the excess fluid re-circulates through pipe 17 back to the reservoir 7. By now turning the selector valve 10 to feed the pressure fluid through pipe 12 to the top of the cylinder the piston 6 is forced down, and at the same time the fluid from below the piston is exhausted through pipes 11 and 13 back to the reservoir 7. As the knife edge 4 strikes the test piece, the springs 25 and 22 slightly compress, and the strain gauges 27, 28 indicate the force applied, and the strain gauges 34 indicate the distance travelled by the piston. Rates of deformation appropriate to the materials will of course be employed, the rate being determined by the speed of the pump drive. In each instance, the displacement of the sample, and of the hydraulic piston, is proportional to the flexing of the flat spring 31. This flexing is then translated into change of resistance of the two attached strain gauges, and from there, by the instrumentation to the oscilloscope deflections. The force applied to the sample is measured by the change in resistance of the strain gauges attached to the elliptical spring loop. The working range is determined by the characteristics of the intermediate spring 25. Springs of suitable moduli may be substituted for any desired working range of deformability. As the test occurs in such a short fraction of a second, temperature control housing is unnecessary. Some materials may be first adjusted to temperature desired and then be placed in the testing apparatus. For instance, some materials may be preliminarily refrigerated. Others may be tested at ordinary temperature.

An essentially straight line relationship exists between thickness of the sample and deformation. Deformability results can thus be reported as per cent of sample thickness.

Other modes of applying the principle of the invention may be employed, change being made as regards the details described, provided the features stated in any of the following claims or the equivalent of such be employed.

We therefore particularly point out and distinctly claim as our invention:

1. In testing apparatus having spaced supporting edges to support a piece to be tested and a movable opposed edge member to apply force at a point intermediate said spaced edges and an element movable through a range equal to the movement of the piece tested and electric translating and viewing means; the combination of a constant drive pump, a reservoir supplying the pump with fluid, a piston and piston rod operated by fluid from said pump, an elliptical spring forming the sole means holding said movable opposed edge member to the end of said piston rod, a collar on the piston rod to move therewith, a flat spring having one end engaging in said collar, a fixed anchorage to hold the other end of said flat spring, strain gauge resistances on said elliptical spring, strain gauge resistances on said flat spring, circuits including the respective resistances, and a pair of indicating means one operated by the circuit from the elliptical spring and the other operated by the circuit from the flat spring.

2. In testing apparatus having spaced supporting edges to support a piece to be tested and a movable opposed edge member to apply force at a point intermediate said spaced edges and an element movable through a range equal to the movement of the piece tested, and electric trans-

lator and viewing means; the combination of constant speed force applying means having a rod, an elliptical spring forming the sole means holding said movable opposed edge member to an end of said rod, a collar on said rod to move therewith, a flat spring having one end engaging said collar, a fixed anchorage to hold the other end of said flat spring, distortion-affected resistances on said elliptical spring, distortion-affected resistances on said flat spring, circuits including the respective resistances, and a pair of indicating means one operated by the circuit from the elliptical spring and the other operated by the circuit from the flat spring.

3. In testing apparatus having spaced supporting edges to support a piece to be tested and a movable opposed edge member to apply force at a point intermediate said spaced edges and an element movable through a range equal to the movement of the piece tested and electric translating viewing means; the combination of a constant speed force applying means having a rod, an elliptical spring forming the sole means holding said movable opposed edge member to the end of said rod, a flat spring having one end anchored and the other movable with the constant speed force applying rod, an electric cir-

cuit controlled by said elliptical spring translating its movement into terms of force, an electric circuit controlled by said flat spring translating its movement into space-traversing terms, and a pair of indicators each controlled by one of said circuits.
